UNITED STATES PATENT OFFICE.

HERMANN BUYTEN, OF DÜSSELDORF, GERMANY.

COMPOUND WOODEN PLATE.

No. 823,843.

Specification of Letters Patent.

Patented June 19, 1906.

Application filed April 9, 1904. Serial No. 202,283.

To all whom it may concern

Be it known that I, HERMANN BUYTEN, a citizen of Germany, residing at Düsseldorf, Germany, have invented new and useful Improvements in Compound Wooden Plates, of which the following is a specification.

This invention relates to an improved compound wooden plate which is composed of an upper veneer, a lower veneer, and an intervening open-work skeleton, which effectively prevents warping of the plate.

In the accompanying drawings, Figure 1 is a top view of my improved compound wooden plate; Fig. 2, a cross-section on line 2 2, Fig. 1; and Fig. 3, a section at right angles to Fig. 2 on line 3 3, Fig. 1.

The letter *a* represents an upper veneer or plate, and *b* is a lower veneer or plate. Between the veneers *a* *b* are arranged three layers of intervening laths or strips *c* *d* *e*, that form a skeleton. The laths of each layer are parallel to each other and are arranged at right angles to the laths of the adjoining layer or layers. Thus the laths *c* of the lowermost layer run at right angles to the laths *d* of the central layer, which in turn are arranged at right angles to the laths *e* of the uppermost layer. The laths of each layer do not contact with each other, but are spaced to form intervening parallel openings, (marked *c'*, *d'*, and *e'*, respectively.) The grain of ad-

joining layers forming the compound plate should cross each other. Thus the grain of veneer *b* runs parallel to the grain of laths *d* and veneer *a*, but at right angles to the grain of laths *c* and *e*. All the parts of the plate are glued together or otherwise connected into one integral structure.

It will be seen that by my invention there is formed between the veneers a perfect lattice truss system, which produces the best attainable stability in all directions with a minimum quantity of material. If desired, the structure may be curved instead of being straight.

What I claim is—

A compound wooden plate composed of an upper veneer and a lower veneer having their grain running in the same direction, a central layer of spaced parallel laths having their grain running in a like direction, and upper and lower layers of spaced parallel laths intermediate the veneers and the central layer and having their grain run at right angles to that of the veneers and the central layer, substantially as specified.

Signed by me at New York city, (Manhattan,) New York, this 8th day of April, 1904.

HERMANN BUYTEN.
